(57) **CLAIM**

The ornamental design for a reclosable bag with tearable header, as shown and described.

DESCRIPTION

FIG. 1 is a perspective view of a reclosable bag with a tearable header on a header pack showing my new design;

FIG. 2 is the perspective view of FIG. 1 with the header pack removed;

FIG. 3 is a front view thereof;

FIG. 4 is a right side view thereof;

FIG. 5 is a top view thereof;

FIG. 6 is a rear view thereof;

FIG. 7 is a left side view thereof;

FIG. 8 is a bottom view thereof;

FIG. 9 is a front elevation view of FIG. 1 wherein the breakaway portions show no specific width;

FIG. 10 is a perspective view of a second embodiment of the reclosable bag with tearable header;

FIG. 11 is a front view thereof;

FIG. 12 is a right side view thereof;

FIG. 13 is a top view thereof;

FIG. 14 is a rear view thereof;

FIG. 15 is a left side view thereof;

FIG. 16 is a bottom view thereof;

FIG. 17 is a perspective view of a third embodiment of the reclosable bag with tearable header on a header pack;

FIG. 18 is the perspective view of FIG. 17 with the header pack removed;

FIG. 19 is a front view thereof;

FIG. 20 is a right side view thereof;

FIG. 21 is a top view thereof;

FIG. 22 is a rear view thereof;

FIG. 23 is a left side view thereof;

FIG. 24 is a bottom view thereof;

FIG. 25 is a front elevation of FIG. 17 wherein the breakaway portions show no specific width;

FIG. 26 is a perspective view of another embodiment of a bag;

FIG. 27 is a front view thereof;

FIG. 28 is a right side view thereof;

FIG. 29 is a top view thereof;

FIG. 30 is a rear view thereof;

FIG. 31 is a left side view thereof; and,

FIG. 32 is a bottom view thereof.

The elements shown in broken line in a dashed, long-short-short-long pattern form no part of the claimed design. The lines of horizontal dashes that appear as broken lines of dashes of substantially equal length indicate lines of perforations, which are aspects of the claimed design. For the bags of FIGS. 1-8, 9, 17-24, and 25, the solid horizontal lines
